PROJECTILE LAUNCHER FOR A GAME

Frank Kohner, Washington Heights, and Albert Stubbmann, New Hyde Park, N.Y., assignors to Kohner Bros., Inc., East Paterson, N.J., a corporation of New York

Filed Apr. 6, 1967, Ser. No. 6,546

Term of patent 14 years

(Cl. D34—15)

FIG. 1

FIG. 2

FIG. 3

FIG. 4

FIG. 5

FIG. 1 is a top plan view of a projectile launcher for a game showing our new design;

FIG. 2 is a side elevational view of said projectile launcher;

FIG. 3 is a front elevational view of said projectile launcher;

FIG. 4 is a rear elevational view of said projectile launcher; and

FIG. 5 is a bottom plan view of said projectile launcher. The conventional numerals are shown in broken lines. The right and left sides of said projectile launcher are identical to one another.

We claim:

The ornamental design for a projectile launcher for a game, substantially as shown and described.
